UNITED STATES PATENT OFFICE.

HENRY S. LOCKWOOD, OF SOUTH NORWALK, CONNECTICUT, ASSIGNOR TO
THE LOCKWOOD MANUFACTURING COMPANY, OF SAME PLACE.

TOY PISTOL.

SPECIFICATION forming part of Letters Patent No. 286,455, dated October 9, 1883.
Application filed January 24, 1883. (Model.)

To all whom it may concern:

Be it known that I, HENRY S. LOCKWOOD, of South Norwalk, county of Fairfield, Connecticut, have invented a new and Improved 5 Toy Pistol, of which the following is a full, clear, and exact description.

My invention relates to that class of toy pistols used for exploding paper caps, and seeks to provide a pistol that shall be perfectly safe 10 and harmless; and it consists in causing the explosion to take place in front of a plate or cup.

Reference is to be had to the accompanying drawings, forming part of this application, in 15 which similar letters of reference indicate corresponding parts in all the figures.

Figure 1 is a side elevation, partly in section, of a toy pistol made in accordance with my invention. Fig. 2 is a plan view of the 20 same; and Fig. 3 is a front elevation of the plate or cup, in front of or in which the explosion takes place, removed from the pistol.

The main body of the pistol, the lock mechanism, and the hammer A are of the ordinary 25 construction.

B is the anvil for exploding the caps, and C is a plate placed between the anvil and hammer A. This plate is preferably cupped, as shown at a, and is preferably made movable by 30 hinging it, as shown, between the side plates of the pistol, so that it may be moved away from the anvil for placing in it the cap to be exploded. When the hammer is brought back for firing, plate C may be made to fall back 35 to the position shown in Figs. 1 and 2, to receive the cap, and so that when the hammer is

released it will strike the plate C and carry it forward with sufficient force against the anvil to explode the cap; or a small spring may be employed for holding the cupped plate constantly against the anvil, except when brought back for putting in the cap. 40

Arranged in this manner the pistol will give a louder report, as the plate forms a sounder and confines the cap at the time of explosion, 45 and at the same time the operator is fully protected against the dust and particles of the cap that are projected by the explosion, as the full force of the explosion is thrown forward and away from the operator by the internal 50 shape of the cup, thus making the pistol perfectly harmless.

I am aware that toy pistols have been made with a recess at the breech of the barrel, a projecting anvil or nipple on an intermediate 55 hammer and the main hammer, the projecting nipple on the intermediate hammer being adapted to explode the cap against the bottom of the recess in the barrel; also, that it is not new to use an intermediate recessed hammer 60 or breech-block.

I claim—

A toy pistol having the cup a arranged on a hinged plate between the hammer and anvil, said cup being adapted to carry the cap against 65 the anvil and cause a louder explosion than usual, as described.

HENRY S. LOCKWOOD.
